MUSICAL INSTRUMENT

Richard T. Cornelius, Minneapolis, Minn.

Application November 22, 1944, Serial No. 564,573

3 Claims. (Cl. 84—1.01)

1

My invention relates to musical instruments and particularly those using a keyboard having lower and upper digitals and has for an object to provide an instrument which will be easier to play in the different keys.

Another object of the invention resides in providing an instrument in which the signature notes are played entirely by the lower digitals of the same notation instead of partly by the upper digitals.

A still further object of the invention resides in providing a musical instrument in which accidental sharps and flats are played by upper digitals.

My invention further relates to musical instruments having diatonic lower digitals and intermediate upper digitals disposed between the lower digitals, the tone generators of which produce tones having a full tone interval and has for an object to provide supplemental upper digitals disposed between the lower digitals, the tone generators of which produce tones having semi-tone intervals, said supplemental digitals being adapted to actuate the tone generators corresponding with either of the lower diatonic digitals adjacent thereto.

Another object of the invention resides in providing a musical instrument having a movable selector member adapted to be moved to various positions, each corresponding with one of the keys, and at such position transferring control of the signature notes to the lower digitals of the same notation.

Other objects of the invention reside in the novel combination and arrangement of parts and in the details of construction hereinafter illustrated and/or described.

In the drawings:

Fig. 1 is a wiring diagram of a musical instrument illustrating an embodiment of my invention.

Fig. 2 is a fragmentary elevational cross sectional view of an electric organ taken on line 2—2 of Fig. 1.

Fig. 3 is a view similar to Fig. 2 taken on line 3—3 of Fig. 1 and drawn to a greater scale.

Fig. 4 is a detailed sectional view through the selector switches taken on line 4—4 of Fig. 2 and drawn to a greater scale.

Fig. 5 is a fragmentary elevational view showing the selector operating member.

Figs. 6 to 19 inclusive are elevational views of the respective cams corresponding with the digitals of the key board.

Figs. 20 to 33, inclusive, are views illustrating

2

the notations of the musical scales in the various keys ordinarily used in writing music.

In the writing of music, the present practice, when keys other than the key of C are being used, is to employ at the beginning of the notation the signature which indicates which of the various notes are to be sharped or flattened in the playing of the piece of music written. This entails considerable mental exertion on the part of the person reading the music and particularly when the key is one having several sharps or flats. Since the notes which are sharped or flattened are different for each key, it requires that the player learn not only which notes are sharped and flattened in each key, but that when he comes to a signature note, he play a different note on the instrument than the one ordinarily played were the piece played in the key of C. This leads to confusion so great that only the most proficient players can read and play music in numerous keys with any degree of speed and few can so read and play in all of the keys. The present invention overcomes this disadvantage by providing a musical instrument in which a selector is moved to a position corresponding to the key to be played and the music then played with disregard to the sharps and flats noted in the signature in much the same manner as if played in the key of C.

To avoid confusion in the specification and claims, the word "key" has been employed to refer to the scales or series of notes used in the playing of a piece while the word "digital" has been used to designate the lever or other manually operated part by means of which each tone generator is actuated. It can readily be understood, however, that the word "digital" is intended to embrace pedals and any other form of manually operated devices arranged in the form of an ordinary key board, such as employed with an organ, piano or the like.

For the purpose of illustration, I have shown my invention as applied to an electrically controlled organ, though it can readily be comprehended that the invention may be used with a piano, harmonium, accordian, or similar instrument.

In Figs. 2 and 3 of the drawings, I have shown a portion of an organ A which includes a manual 15 mounted in a case 16. This manual comprises a number of digitals arranged in octaves. Since the invention is merely duplicated in each octave, only the digitals in one octave have been shown. These digitals consist of lower digitals 21, 22, 23, 24, 25, 26, 27 and 28, which correspond with tone

generators producing the tones customarily referred to in music as C, D, E, F, G, A, B and C. Between the digits 21 and 22 and between the digits 22 and 23 are upper digits 31 and 32 which correspond with the tone generators producing the tones C sharp D flat and D sharp E flat. Likewise, between the lower digits 24 and 25, between the digits 25 and 26, and between the digits 26 and 27 are disposed upper digits 33, 34 and 35. These digits correspond with the tone generators producing the tones F sharp G flat, G sharp A flat, and A sharp B flat.

The particular organ illustrated is a pipe organ and the tone generators consist of a number of pipes with suitable wind apparatus for sounding the same. Such construction being well known in the art has not been shown in detail in the drawings. It is to be noted that there are a number of pipes 41, 42, 43, 44, 45, 46, 47 and 48 which correspond with the digits 21, 22, 23, 24, 25, 26, 27 and 28 and which are tuned to produce the tones customarily designated as C, D, E, F, G, A, B and C, forming the tones of the diatonic scale. For the sake of convenience, these tone generators have been referred to as the diatonic tone generators and the digits corresponding therewith as the lower or diatonic digits. In addition to the tone generators above referred to, other pipes 51, 52, 53, 54 and 55 are employed which are tuned to produce the tones C sharp D flat, D sharp E flat, F sharp G flat, G sharp A flat, and A sharp B flat. These pipes correspond with the digits 31, 32, 33, 34 and 35 and produce tones which are intermediate the tones of the adjacent diatonic pipes having a semi-tone interval with reference to said tones. Said tone generators and the digits corresponding therewith have hence been referred to as the upper intermediate tone generators and digits. Of the diatonic tone generators, the tones produced by the pipes 43 and 44 and by the pipes 47 and 48 have a semi-tone interval, while the tones produced by the other diatonic tone generators have a full tone interval.

Each of the digits of the organ consists of a lever 59 which is pivotally supported on a balance rail 61. This lever rests on a felt pad 62 secured to said balance rail. A pin 63 passes loosely through the lever 59 and is driven into the rail 61 and forms a hinge for the lever. The rail 61 is carried by a key bed 64 which also supports a stop rail 65. This rail has pins 66 issuing upwardly therefrom which fit loosely in holes 67 in the under sides of the levers 59. Extending upwardly from the digits and at a location near the balance rail 61 is a front panel 68. The front panel 68 and bed 64 form part of the case 16 which also includes a top 69 and end walls 56.

The levers 59 extend into the case 16 and each lever operates an actuating switch which closes a circuit energizing a solenoid operated valve which directs air into the particular tube to be blown. For supporting these switches, an actuating switch bar 57 is employed which is attached to the end walls 56. These switches are mounted on said bar and are designated by the reference numerals 71, 72, 73, 74, 75, 76, 77, 78, 81, 82, 83, 84 and 85 and correspond with the digits 21, 22, 23, 24, 25, 26, 27, 28, 31, 32, 33, 34, and 35, respectively. Since all of these switches are identical, only the switch 75, which is associated with digital 25, has been shown in detail in the drawings and will be described.

The switch 75 comprises two blades 89 and 91, which are attached to and insulated from one

another by means of insulating blocks 92 and 93. Screws 94 hold the said parts in position and secure the same to the actuating switch bar. The switch blades 89 and 91 have contacts 95 secured to the ends of the same which are adapted to make contact when the blade 91 is urged toward the blade 89. For this purpose, a screw 96 is threaded into the end of the lever 59 and engages the under side of the blade 91. When the digital is depressed, screw 96 is raised and the switch 75 is closed. For the purpose of returning the digital to normal position, a spring 97 is employed which acts between the under side of the bar 57 and the inner end of the lever 59. The return movement of the digital is terminated when the lever 59 engages a stop bar 98 secured to the bed 64.

Associated with each digital is a cam, said cams being designated by the reference numerals 101, 102, 103, 104, 105, 106, 107, 108, 111, 112, 113, 114, and 115, and corresponding with the digits 21 to 28 and 31 to 35, respectively. These cams are shown in detail in Figs. 6 to 19, inclusive. The form of said cams will be presently described in detail. Said cams are mounted on and keyed to a shaft 119 journaled in suitable bearings (not shown) which are carried by the end walls 56 of case 16. The shaft 119 has also mounted on it a bevel gear 121 which meshes with another bevel gear 122 fast on a stub shaft 123 shown in Fig. 5. This shaft is journaled in a bearing 124 secured to the panel 68 and passes completely through said panel. On the outer end of shaft 123 is mounted a knob 125 by means of which said shaft may be rotated. This knob has a pointer 126 on it which moves along a scale 127 fast on the panel 68. The scale 127 has fourteen positions on it, designated 128, which are marked with the key notes of the various scales ordinarily used in writing and playing music. When the knob is turned to cause the pointer to point at a particular scale, the various cams become arranged in such a manner that the proper tone generators are sounded when the digits are depressed.

Associated with the respective cams 101 to 108 and 111 to 115 are multiple switch sets designated by the reference numerals 131 to 138 and 141 to 145, inclusive. Each of these switch sets includes three switches and the said switches will be designated by the same reference characters as the switch set to which it belongs and to which have been added the sub-characters *a*, *b* and *c*. For the switch set 135, the three switches will be 135*a*, 135*b* and 135*c*. Only the switches of the switch set 135 have been shown in detail, which are illustrated in Fig. 2. For supporting the switches of the various switch sets, I employ a selector switch bar 171 which is attached to the end wall 56 of case 16. This switch bar has attached to it pairs of contacts, as disclosed in Fig. 4, indicated by the reference numerals 129 and 130. Two of these contacts, together with a movable connector 172, form each switch. The connector 172 has issuing from it two contacts 173 adapted to contact the contacts 129 and 130 to close the circuit connecting the same. The connector 172 is attached to an arm 174 which, in turn, is pivoted to a switch lever 175. Lever 175 is mounted for oscillation on a shaft 176 which extends across to the end wall 56 of cabinet 16 at a position above the actuating switch bar 57. The lever 175 has a cam follower 177 which is adapted to engage the surface of the cam 105 with which it is associated. A spring 178, acting between an ex-

tension 179 on the lever 175 and a screw eye 181 secured to the panel 68, maintains the cam follower 177 in engagement with the cam. Another spring 182, acting between the lever 175 and an extension 183 on arm 174, serves to maintain the contacts 173 urged toward the bar 171 and when the said contacts are in proper position against the contacts 129 and 130. While I desire to employ switches having two contacts with a connector for connecting the same together, it can readily be comprehended that single contacts can be used on the switch bar and, likewise, a single contact used on the movable arm 174 shown in Fig. 2 which carries the connector 172. In this case, however, it will become necessary that the current be carried through the arm 174 and the lever 175 which will entail pigtailed or other types of flexible connections. Since the illustration of the wiring of the invention is much simplified by showing the single type of contact, I have so illustrated the wiring in Fig. 1. It will be readily comprehended that where the double contacts are used, the additional contacts are all connected together and to the same conductors as the arms shown in Fig. 1 are connected. In such case, the arms would be out of the electrical circuits.

In addition to the upper digitals 31, 32, 33, 34 and 35, I employ two additional upper digitals 36 and 37 which are situated between the digitals 23 and 24 and between the digitals 27 and 28. These upper digitals are similar to the digitals 31-35, excepting that the same are made to differentiate therefrom in being slightly lower in height and being made white instead of black. These digitals operate actuating switches 86 and 87 corresponding with the similar switches employed for the other digitals. In connection with the digitals 36 and 37, additional cams 116 and 117 are employed which control multiple switch sets 146 and 147, which, however, differ from the other switch sets in that the switch sets have only two switches 146a and 146c and 147a and 147c. The cams 116 and 117 have, however, three positions, but the intermediate positions between switches are open.

In Figs. 20-33, I have shown the various keys or scales ordinarily used in writing and playing music, and have shown the various notes which are sharped and flattened for each key. In the drawings, the invention has been shown as arranged to play in the key of A and the description of the various parts and their relations will be discussed with reference to this key. In Fig. 25, the scale for the key of A has been shown. In this figure, the signature is indicated at 184 and shows three sharps, namely, C sharp, F sharp and G sharp. Beneath the notes 185 of the scales are also indicated the letters which correspond with the tones to be played. It will be noted that in this scale, all of the notes except C sharp, F sharp and G sharp are played by the lower digitals. In order to play C sharp, F sharp and G sharp by lower digitals, it becomes necessary to transfer actuation of the corresponding tone generators, which would be 51, 53 and 54 to the digitals 21, 24 and 25. This is accomplished by means of the various cams 101 etc. It will be noted in Figs. 6-19, inclusive, that the cams have three radial circumferential paths which determine the position of connector 171. When the cam follower is at the outermost portion of the cam, switch 135c is closed. When at its intermediate position, switch 135b is closed, and when at its inner position, switch 135a is

closed. The cams are so designed that each cam causes the proper closure of the switch associated therewith, whereupon the sharps and flats of the signature may be all played by the lower digitals.

For the purpose of operating the various tone generators 41 to 48 and 51 to 55, inclusive, a number of solenoids 151 to 158 and 161 to 165, inclusive, are employed which correspond with said tone generators. These solenoids operate valves not shown which control the flow of air to the various pipes or tone generators. Such construction being well known in the art, has not been described in this application, though it can be readily comprehended that any suitable construction now available for the purpose may be employed. For energizing the solenoids, a line 186 is employed which is connected to a suitable source of electrical energy and which has two conductors 187 and 188. Conductor 187 is connected to one side of each of the solenoids 151 to 158 and 161 to 165, inclusive. The other conductor 188 of the line 186 is connected to one side of all of the switches 71 to 78 and 81 to 85, inclusive. The other sides of these switches are connected by means of conductors 191 to 198 and 201 to 205, inclusive, with the contacts 129 of the switches 131 to 138 and 141 to 145, inclusive. This is equivalent to connecting the said conductors to the levers 175, as shown in the wiring diagram.

The other sides of the various solenoids 151 to 158 and 161 to 165 are connected to the various selector switches 131 to 138 and 141 to 145, in the following manner. Solenoid 151 is connected by a conductor 211 to the switch 131b and by means of another conductor 212 to the switch 141a. Solenoid 161 is connected by means of conductors 213, 214 and 215 with switches 131c, 141b and 132a. Solenoid 152 is connected by means of conductors 216, 217 and 218 with switches 141c, 132b and 142a. Solenoid 162 is connected by means of conductors 219, 220 and 221 with the switches 132c, 142b and 133a. Solenoid 153, which corresponds to the tone E, is, however, connected somewhat differently. This solenoid is connected by means of conductors 222, 223, 224 and 225 with the switches 142c, 133b, 146a and 134a. Solenoid 154 is connected similarly to the solenoid 153 by means of conductors 226, 227, 228 and 229 with the switches 133c, 146b, 134b and 143a. Solenoid 163 is connected by means of conductors 231, 232, and 233 with switches 134c, 143b and 135a. Solenoid 155 is connected by means of conductors 234, 235 and 236 with switches 143c, 135b and 144a. Solenoid 164 is connected by means of conductors 237, 238 and 239 with switches 135c, 144b and 136a. Solenoid 156 is connected by means of conductors 240, 241 and 242 with switches 144c, 136b and 145a. Solenoid 165 is connected by means of conductors 243, 244 and 245 with switches 136c, 145b and 137a. Solenoid 157 is connected similarly to the solenoid 153 by means of conductors 246, 247, 248 and 249 with the switches 145c, 137b, 147a and 138a. Solenoid 158 is connected by means of conductors 251, 253 and 254 with the switches 137c, 147c and 138b. It will readily be comprehended that the manner of connecting the various solenoids and switches continues throughout the adjoining octaves and is duplicated in each octave.

In the design of the various cams 101 to 108 and 111 to 117, the surfaces of the cams are so arranged that when the knob 125 and pointer 126 indicate a particular key, the actuation of

the generators producing the sharped or flatted tones designated by the notes of the signature are transferred to the lower digitals having the same notation. As an example, the instrument has been shown in the drawings as set to play the key of A. Fig. 25 shows that C, F and G are the only notes which are sharped. In examining the various digitals, it will be found that in Fig. 6 the follower opposite the key of A is on the outermost path. Referring to Fig. 2, it will be noted that the switches corresponding to the reference character C are closed when the follower is following along the outermost path. In Fig. 1, the digital 21, which corresponds to tone C, operates a circuit controlled by the cam 101 and the switch set 131. In this case, the switch 131c is closed and the circuit will be traced through solenoid 161 which controls the operation of pipe 51 producing C sharp. In similar manner, the cams 104 and 105 shown in Figs. 12 and 14 which correspond with tones F and G, which are also sharped are so constructed that the cam followers are on their outer paths and depression of the digitals 24 and 25 causes the solenoids 163 and 164 to become actuated and to operate the tone generators 53 and 54 which play F sharp and G sharp. The cams of all of the other lower digitals are arranged so that the followers operate along the intermediate path and which, from an inspection of Fig. 1, will show that in such position, the digitals play the tone actually corresponding with said digitals.

With my invention, all incidental sharps and flats are played by the upper digitals. In order that this be possible, the two extra upper digitals 36 and 37 are employed which, when the cam follower of the cams corresponding therewith are in their outermost or innermost positions, cause these digitals to play either of the tones normally played by the adjacent lower digitals and when in their intermediate positions to play no tone whatsoever. In other words, digital 36 will play either E or F or no tone whatsoever and the digital 37 will play B or C or no tone whatsoever. Inasmuch as an incidental sharp of one intermediate tone, namely, a tone played by an upper digital, becomes a natural, it will be noted that the cams corresponding to the intermediate tones are so constructed that the cam followers are on the outer paths of the cams. This changes the tones played by the upper digitals to the proper natural tones. It will readily be comprehended that all of the keys are worked out in the same manner, so that the proper tones are produced when the desired digitals are depressed.

The use of my invention greatly simplifies the playing of music. The player first reads the signature of the piece of music and turns the knob 125 until the pointer 126 is opposite the same key. He then plays the notes as written, disregarding the signature and playing the signature notes by the lower digitals having the same notation. In other words, instead of playing C sharp, F sharp and G sharp in the key of A, he merely plays C, F and G, and the instrument automatically causes the proper sharp tones to be played. When he comes to accidental sharps, he plays the adjacent upper digital to the right and when he comes to accidental flats, he plays the upper adjacent digital to the left. This applies to the tones E and F, as well as the tones B and C. In such case, the supplemental digitals 36 and 37 are used. When playing in a sharped key and a natural accident occurs, the player treats it as a flat, and if he is playing in

5 a flatted key, he merely treats it as a sharp. In this manner, the player merely reads the notes as they occur and does not have to carry in mind the particular notes which are sharped and flatted in the signature.

6 The advantages of my invention are manifest. With my invention, a minimum amount of memory work is imposed upon the player. The player using my instrument can learn to play with a minimum amount of practice. Players using my improved instrument can learn to play more rapidly and far more accurately. With my instrument, it becomes only necessary to play in the key of C, the invention reducing all other keys to the equivalent of C. With my invention, there are far less opportunities for errors in the playing of pieces of music in keys having several sharps and flats. My invention may be readily applied to any mechanical instrument having a manual or key board arranged in the conventional manner such as pianos, organs, melodions or accordions.

7 Changes in the specific form of my invention, as herein described, may be made within the scope of what is claimed without departing from the spirit of my invention.

8 Having described my invention, what I claim as new and desire to protect by Letters Patent is:

1. In a musical instrument having diatonic tone generators adapted to produce a diatonic scale, and lower digitals corresponding therewith and further having intermediate tone generators producing semitones between the full tones of the diatonic scale and upper digitals corresponding therewith, means for actuating each tone generator by the digital corresponding therewith, means for actuating each of the intermediate tone generators by one of the juxtaposed lower digitals, supplemental upper digitals disposed between the lower digitals whose generators produce tones having semitone intervals, means for causing said supplemental digitals to actuate the tone generators corresponding with either of the lower digitals adjacent thereto, and selector means for selectively predetermining the digital by which each generator is actuated.

2. In a musical instrument having diatonic tone generators adapted to produce a diatonic scale, and lower digitals corresponding therewith and further having intermediate tone generators producing semitones between the full tones of the diatonic scale and upper digitals corresponding therewith, electrical means for actuating each of said tone generators, three switches associated with each of said digital, circuits connecting one of the switches of each digital with the tone generator corresponding with said digital, circuits connecting another of the switches of each digital with the tone generator producing a tone a semitone lower than that produced by the tone generator with which the first switch is associated, circuits for connecting the other of said switches of each digital with the tone generator producing a tone a semitone higher than that produced by the tone generator with which the first switch is associated, supplemental upper digitals disposed between the lower digitals whose generators produce tones having semitone intervals, two switches associated with each of said supplemental digitals, circuits connecting one of said switches of each supplemental digital with the tone generator corresponding with the digital to the left of said supplemental digital, circuits connecting the other of said switches of each supplemental digital with the tone generator corresponding with the generator to the right of said

supplemental digital, and selector means for selectively predetermining the switch by means of which each tone generator is actuated.

3. In a musical instrument having tone generators, digitals corresponding therewith, means for effecting control of said generators by their corresponding digitals and means for retaining control of certain of said generators by their corresponding digitals and for concurrently shifting control of certain of the other of said tone generators to the digitals adjacent the digitals corresponding therewith.

RICHARD T. CORNELIUS.
